PAINT APPLYING DEVICE

Leib Sultanik and Sam Sultanik, Brooklyn, N. Y.

Application March 28, 1951, Serial No. 217,983

2 Claims. (Cl. 15—132.5)

1

This invention relates to paint applying devices, more particularly of the type for applying a pattern to a wall or like surface.

It is among the objects of the invention to provide a paint applying device that has but few parts which may readily be fabricated from relatively low cost materials and which is not likely to become out of order, which device may readily be disassembled for cleaning and may be used by even an unskilled workman to apply a pattern on a relatively large wall or like surface without need for stopping to replenish the paint supply and with which patterns in several colors may be applied.

According to the invention these objects are accomplished by the arrangement and combination of elements hereinafter described and particularly recited in the claims.

In the accompanying drawings in which is shown one of various possible embodiments of the several features of the invention,

Fig. 1 is a rear elevational view of the device,

Fig. 2 is a transverse cross sectional view taken along line 2—2 of Fig. 1,

Fig. 3 is a perspective view of the paint reservoir.

Fig. 4 is a perspective view of one of the roller mounting arms,

Fig. 5 is a perspective view of one of the reservoir partitions, and

Fig. 6 is a longitudinal sectional view of the device taken along line 6—6 of Fig. 2.

Referring now to the drawings, the paint applying device desirably comprises a paint reservoir 11 desirably in the form of an elongated trough which has parallel end walls 12 and 13, and parallel side walls 14 and 15, one of said walls, illustratively wall 15 having a handle 16 extending outwardly therefrom.

The reservoir desirably has a plurality of compartments 17 therein formed by means of spaced separator plates or partitions 18 and 19 extending transversely across the reservoir between the side walls 14 and 15 thereof.

Although the separator plates may be permanently mounted in the reservoir, it is preferred to make them removable. To this end the bottom wall 20 and side walls 14 and 15 of the reservoir each has a pair of spaced transverse grooves 21 therein of width sufficient to receive the bottom and side edges of the separator plates and snugly to retain the latter to prevent seepage of paint from one compartment to the other.

Each of the end walls 12 and 13 of the reservoir has a channel member 26, 27 affixed thereto respectively and extending vertically thereon, said channel members defining an elongated socket 28 to receive the lower end 29 of a supporting arm 30, 31 respectively.

Although arms 30 and 31 may be of any suitable construction, as shown in Fig. 4, they each

2

desirably comprise a length of relatively heavy wire reversely bent as at 31 and 32 to form two parallel legs 33 and 34, the end 31 of the arms being filled in as with solder as at 40 to form a bearing 40'.

The portions 35, 36 of arms 30 and 31 which rise above the upper edges 37 of side walls 12 and 13 of the reservoir are desirably bent away from side wall 15 at an oblique angle of substantially 45 degrees with respect to the lower end 29 thereof.

Desirably, the adjacent free ends of legs 33, 34 of arm 30 are affixed together as by welding and the free ends 43, 44 of legs 33, 34 of arm 31 are spaced from each other.

Slidably mounted on the free end 43 of leg 33 of arm 31 is a locking member 46, desirably a metal tube which may be moved by handle 47 thereon upwardly on leg 33 so that the end 48 of the tube 46 may slide over the free end 44 of leg 33 to close the space between ends 43 and 44.

As shown in Figs. 2 and 6 a paint transfer roller 51, 52 and 53 is positioned respectively in each of the compartments 17 in the reservoir 11. Each roller is desirably of rubber, although any other suitable material may be used and has an axle 54 suitably mounted in the associated compartment. To this end each of the separator plates or partitions 18 and 19 has a vertical channel 55 on each side thereof open at its upper end 56, the bearing 40' on end wall 12 and the associated channel 55 on plate 18 rotatably mounting the roller 51, the associated vertical channels on plates 18 and 19 rotatably mounting the roller 52 and the bearing 40' on end wall 13 and associated channel 55 on plate 19 rotatably mounting the roller 53.

As shown in Fig. 2, the diameter of the rollers 51, 52 and 53 is such that the upper periphery 59 thereof extends above the associated cut away portion 61 in the upper edge of each of the partitions and such upper periphery 59 is in engagement with a paint receiving roller 63.

As shown in Figs. 2 and 6, roller 63 which may be of any suitable material and desirably is of metal, has an axle 64 extending parallel to the axles 54 and which rides in the space between legs 33 and 34 of the arms 30 and 31, thereby rotatably mounting said roller which will be retained by gravity in engagement with paint transfer rollers 51, 52 and 53.

Roller 63 desirably has a plurality of closely spaced parallel transverse annular grooves 65 in the periphery thereof in which the paint conveyed thereto by the transfer rollers will adhere, to ensure that a ring of paint will be applied around the entire circumference thereof.

Associated with paint receiving roller 63 is a paint spreading roller 68 which also is desirably of metal and has an axle 69 extending parallel to axle 64 and which also rides in the space

between legs 33 and 34 of arms 30 and 31 thereby by rotatably mounting such roller which will be retained by gravity against the periphery of the paint receiving roller 63.

Roller 68 desirably has a plurality of parallel longitudinal grooves 72 in its periphery which, when in engagement with the annular grooves 65 in roller 63 will cause the paint to spread longitudinally over roller 68.

Associated with paint spreading roller 68 is a paint applying roller 74 which desirably has an axle 75 extending parallel to axle 69, which also ride in the space between legs 33 and 34 of arms 30 and 31, thereby rotatably mounting roller 74 which also will be retained by gravity against the periphery of the paint receiving roller. Roller 74 desirably has an outer surface 77 of resilient material such as soft rubber which is preferably formed with a pattern thereon so that the paint picked up from the paint spreading roller 68 may be applied to a wall or other surface to form the desired design.

Operation

To use the device, the compartments 17 may be filled with paint of different colors as desired. The operator may then grip handle 16 and press the paint applying roller 74 against the wall to be painted and thereupon move the roller 74 against such wall.

If, for example, the roller 74 is moved downwardly it will rotate in a clockwise direction as shown in Fig. 2. Roller 68 will rotate in a counterclockwise direction, roller 63 in a clockwise direction and transfer rollers 51, 52 and 53 in a counterclockwise direction.

Such rotation of the transfer rollers will cause the latter to pick up paint from the associated compartments and apply such paint to paint receiving roller 63. As a result of the annular grooves 65 in roller 63, the paint will adhere thereto in a ring therearound thereby to prevent lateral spreading of such paint.

The paint on roller 63 will be conveyed to spreading roller 68 and by reason of the longitudinal grooves 72 in the latter be distributed longitudinally thereof to be picked up by the entire length of the paint applying roller 74 to be applied to the wall being painted.

By reason of the construction above described, the paint will be applied to the wall in vertical stripes with substantially no mixing of such paint except at the lateral edges of the stripes where the paints will blend slightly to produce a rather attractive effect.

By reason of the soft rubber surface of the paint applying roller, the paint will adhere thereto so that the pattern painted on the wall will not be spotty or interrupted.

To clean the device, it is a simple matter to move the locking member on leg 33 of arm 31 to the position shown in Fig. 4. The rollers 63, 68 and 74 may thereupon be lifted along the spaces between the legs 33, 34 until their axles are aligned with the space between ends 43 and 44 and thereupon removed from the arms.

The transfer rollers may then be removed by lifting them from the associated compartments and the arms 30 and 31 may be removed by withdrawing them from their pockets 28. The disassembly may be completed by sliding the partitions from the grooves 21.

With the construction above described, a highly efficient paint applying device is provided which may be used continuously for long periods

by reason of the relatively large capacity of the paint carrying compartments thereof to paint patterns of any desired design on a wall in parallel stripes.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described our invention, what we claim as new and desire to secure by Letters Patent of the United States is:

1. A paint applying device comprising a reservoir having parallel end and side walls respectively, a partition extending transversely across said reservoir between said side walls to define compartments in said reservoir, said partition being removably mounted in said reservoir, a paint transfer roller rotatably mounted in each of said compartments on an axis at right angles to said end walls, a paint receiving roller extending parallel to the axis of said transfer rollers and in engagement with the latter, a paint spreading roller extending parallel to said transfer roller and in engagement with said paint receiving roller, a paint applying roller extending parallel to said paint spreading roller and in engagement therewith and means rotatably mounting said paint receiving roller, said paint spreading roller and said paint applying roller.
2. A paint applying device comprising a reservoir having parallel end walls, a channel member defining an elongated socket affixed to each of said end walls extending vertically thereon, a pair of arms removably affixed respectively at one end in said sockets on each of said end walls and rising above the upper edge thereof, said arms being bent at an oblique angle above said upper edge, a plurality of equally spaced partitions extending transversely across said reservoir defining a plurality of compartments therein, said partitions being removably affixed in said reservoir, a vertical channel affixed on each side of said partition, said channels being open at their upper ends, a paint transfer roller rotatably mounted in each of the compartments of said reservoir on an axis at right angles to said end walls, each of said paint transfer rollers having an axle bearing at each end in an associated pair of vertical channels on said partitions and on the end walls of said reservoir, a paint receiving roller, a paint spreading roller and a paint applying roller each of such rollers having an axle extending parallel to the axes of said paint transfer rollers and rotatably mounted on said arms, said rollers being in engagement with each other and with said transfer rollers.
